(57) CLAIM

I claim the ornamental design for a tray with foot-like impressions, as shown and described.

DESCRIPTION

FIG. 1 is a perspective view of a tray with foot-like impressions showing my new design;

FIG. 2 is a top view thereof;

FIG. 3 is a bottom view thereof;

FIG. 4 is a front view thereof;

FIG. 5 is a left view thereof;

FIG. 6 is a right view thereof; and,

FIG. 7 is a back view thereof.

The broken lines are included for the purpose of illustrating environment and form no part of the claimed design.
